TUYÈRE

Nicholas Even, Excelsior, Minn., assignor to Minneapolis-Moline Company, Hopkins, Minn., a corporation of Minnesota

Application July 14, 1950, Serial No. 173,780

13 Claims. (Cl. 266—41)

1

This invention relates to improvements in tuyères for the walls of blast furnaces or cupolas, used in melting iron and the like in foundries, and which tuyères control the admission of air for combustion.

The primary object of my invention is to provide a tuyère of novel construction which will so control and direct the air blast as to materially improve the production and efficiency of such furnaces, and which will permit convenient and precise control of the air.

Another object is to provide a tuyère which will direct the air blast downward into the furnace to the point where it will materially and measurably increase the combustion efficiency.

Still another object is to provide a tuyère having a draft control gate, or gates, with fins thereon movable with the gates, as they are opened, into the air passage into such position as to angle and direct a part of the air blast downward and inward into the combustion chamber.

These and other more detailed and specific objects will be disclosed in the course of the following specification reference being had to the accompanying drawings, in which—

Fig. 1 is a perspective view of a complete tuyère according to my invention, viewing the same from the outer or inlet side.

Fig. 2 is a vertical cross sectional view, with parts of the operating mechanism for the draft gates omitted.

Fig. 3 is a horizontal sectional view, also with a part of the operating mechanism omitted and showing one draft gate open and the other closed, the view being taken along the line 3—3 in Fig. 2.

Referring now more particularly and by reference characters to the drawing, A designates generally the tuyère of my invention, same being adapted to set in the wall B of a conventional blast furnace or cupola in order to control and direct air for combustion into the interior thereof, as indicated by the arrows. The tuyère comprises a housing or tuyère box 10 with inwardly diverging or flaring end walls 11, top 12 and bottom 13 forming an inwardly, horizontally flaring air passage as will be clearly apparent. Preferably, also, the inner part of the bottom 13 angles downward in the direction of air delivery, as seen in Fig. 2, since the lower strata of inflowing combustion air angles and flows downward as will presently appear.

The narrower, outer or inlet end of the box 10 may be selectively closed off by complementary draft gates or doors 14—15 each of which has a vertical pintle or trunnion 16 journaled in spaced

relation into the top 12 and bottom 13 of the box. The arrangement is such that the gates 14—15, when swung in one direction, will close off this outer end of the box and when swung in the opposite direction will move to parallel positions at which they will offer little resistance to inward air travel and thus open the tuyère box. The gate 14 is shown open in Fig. 3 and the gate 15 closed. The gates are moved to and between these positions by separate actuating racks 17—18 meshing with gears or gear teeth 19 on the upper ends of the pintles 16 and these racks are slideable, inwardly and outwardly, in recesses 20 formed in the underside of the top 12 (Fig. 2) and through a guide bracket 21 secured at 22 to the outer end of said top. Outwardly of the tuyère the racks 17—18 diverge at 23 and are pivotally attached at 24 to separate rock levers 25—26, the latter being fulcrumed at 27 to bracket 28 extending outward and upward from the outer end of the tuyère box bottom 13, as seen in Fig. 1. To the lower ends of the rock levers 25—26 I then pivot at 29 suitable control mechanism such as represented by the links 30 and separate knobbed control handles 31—32. Thus, by moving the handles 31—32 the racks 17—18 may be adjusted to open and close either or both draft gates 14—15 as required to properly regulate the air inflow to the combustion chamber of the furnace and as will be readily understood.

For the journal accommodation of the upper and lower ends of the pintles 16 the top and bottom of the tuyère box is provided with suitable bearing openings, designated throughout at 33 (Fig. 2).

The draft gates 14—15 carry air directing vanes or fins 34—35 on their inner surfaces and at or above the midway point of the gates vertically. These vanes are formed integrally with, or secured in any suitable fashion to, the gates and however formed are angularly disposed with respect to the horizontal so as to angle inwardly and downwardly when the gates are open, as seen in Fig. 2. Thus the lower strata or part of the air entering through the tuyère will be deflected in a downward direction into the furnace and I find that this movement of the air brings it to the point where most needed, with a resulting increase in combustion efficiency such as to materially increase the production capacity for a given furnace. The importance of this feature will thus be readily apparent to those skilled in the art. This downward deflection of the air also has the beneficial effect of preventing bridging of material over the tuyères. This bridging oc-

curs at present over the lower tuyères but I find that by using for the upper tuyères a construction such as that herein disclosed that the downward flow of air from these upper tuyères will break up the tendency of air to flow upwardly just inside the inner wall of the cupola and will cause the air to penetrate the material toward the center of the cupola, with better combustion resulting. It is my belief that it is this upwardly flowing and comparatively cool air which cools the material sufficiently to cause it to harden and bridge over the lower tuyères, making it necessary to periodically introduce a tool through these tuyères and break up the hardened bridged material.

As viewed from above the vanes 34—35 are sector or quadrant shaped, as shown in Fig. 3, having arcuate outer edges 36 and the shape and size of the vanes is further such that they will substantially completely span the spaces outside of the gates as they open. Thus the air flowing through these spaces will be guided and directed as desired while the vanes will in no way interfere with the opening and closing movements of the gates.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. A tuyère of the character described, comprising a tuyère box having an air passage therethrough, a draft gate pivotally mounted in the box, means for opening and closing the gate to control the passage of air, and a vane on the gate for deflecting a part of the air passing through the box.

2. In a tuyère for the wall of a blast furnace, a tuyère box having an air passage for directing air into the furnace, a draft gate pivotally mounted in the box and movable to and between open and closed positions for controlling air flow through said passage, and a vane on the draft gate movable therewith as the gate opens into a position for deflecting a part of the air downward through said passage into the furnace.

3. In a tuyère for the wall of a blast furnace, a tuyère box having an air passage for directing air into the furnace, a draft gate pivotally mounted in the box and movable to and between open and closed positions for controlling air flow through said passage, and a vane on the draft gate movable therewith as the gate opens into a position for deflecting a part of the air downward through said passage into the furnace, the said tuyère box having a bottom angled downward in the direction taken by the air deflected by said vane.

4. In a tuyère for the wall of a blast furnace, a tuyère box having an air passage for directing air into the furnace, a draft gate pivotally mounted in the box and movable to and between open and closed positions for controlling air flow through said passage, and a vane angularly positioned on the upper part of the gate for directing a part of the air downward into the furnace when the gate is opened.

5. A tuyère of the character described for controlling and directing air inflow to a blast furnace, comprising a tuyère box having an opening into the furnace, a gate pivoted at upper and lower ends inside the box and swingable from a closed position to an open position at which an air pas-

sage is formed alongside the gate, an angular vane on the gate swingable therewith and having an arcuate edge whereby the vane will swing across said air passage as the gate is opened and thereby deflect a part of the air flowing into the furnace.

6. A tuyère of the character described for controlling and directing air inflow to a blast furnace, comprising a tuyère box having an opening into the furnace, a pair of gates pivoted at upper and lower ends inside the box alongside each other and swingable from closed positions to parallel positions to open the box, and vanes angularly set on the gates to span part of the opening through the box when the gates are opened and direct a part of the air downward into the furnace.

7. A tuyère of the character described for controlling and directing air inflow to a blast furnace, comprising a tuyère box having an opening into the furnace, a pair of gates pivoted at upper and lower ends inside the box alongside each other and swingable from closed positions to parallel positions to open the box, and vanes angularly set on the gates to span part of the opening through the box when the gates are opened and direct a part of the air downward into the furnace, the said tuyère box having diverging portions flaring into the furnace to disperse the air thereinto.

8. A tuyère of the character described for controlling and directing air inflow to a blast furnace, comprising a tuyère box having an opening into the furnace, a pair of gates pivoted at upper and lower ends inside the box alongside each other and swingable from closed positions to parallel positions to open the box, vanes angularly set on the gates to span part of the opening through the box when the gates are opened and direct a part of the air downward into the furnace, gear teeth on the gates, racks slidably supported on the box in meshing engagement with said teeth, and means for separately sliding the racks to open and close the gates.

9. A tuyère of the character described for controlling and directing air inflow to a blast furnace, comprising a tuyère box having an opening into the furnace, a pair of gates pivoted at upper and lower ends inside the box alongside each other and swingable from closed positions to parallel positions to open the box, vanes angularly set on the gates to span part of the opening through the box when the gates are opened and direct a part of the air downward into the furnace, gear teeth on the gates, racks slidably supported on the box in meshing engagement with said teeth, and means for separately sliding the racks to open and close the gates, the said means comprising brackets on the tuyère box, rock levers fulcrumed on the brackets and pivotally connected at one end to the racks, and knobbed handles linked to the opposite ends of the rock levers.

10. In a tuyère for a cupola, a tuyère box having an air passage to direct air inwardly into the cupola, at least one draft gate adjustably mounted in the box to regulate the flow of air therethrough, and a vane on the gate inwardly and downwardly angularly positioned with respect to the horizontal to direct the inflowing air downward from the box.

11. In a tuyère for a cupola, a tuyère box having an air passage to direct air inwardly into the cupola, at least one draft gate pivoted on a vertical axis in the box to control the flow of air

therethrough, and a vane on the gate angled inward and downward to correspondingly direct the flow of air inward through the box.

12. A tuyère of the character described for controlling and directing air inflow to a blast furnace, comprising a tuyère box having an opening into the furnace, a pair of gates having separate pivot connections in the box and swingable about said connections in generally horizontal planes to regulate air flow through the box, and vanes angularly located on the gates to direct the inflowing air downward.

13. A tuyère of the character described for controlling and directing air inflow to a blast furnace, comprising a tuyère box having an opening 15 into the furance, a pair of gates having separate

pivot connections in the box and swingable about said connections in generally horizontal planes to regulate air flow through the box, vanes angularly located on the gates to direct the inflowing air downward, and separate means for independently adjusting the gates.
